THERMOMETER CASING WITH THERMOMETER ILLUMINATING MEANS

Sophia M. Chomes, Watertown, Mass.

Application June 21, 1947, Serial No. 756,171

3 Claims. (Cl. 240—6.4)

1

This invention relates to devices for illuminating the graduated portion of a thermometer, and more particularly a clinical thermometer, in such a manner as to facilitate the reading of its indication, and it has for one object to provide such a device which so localizes the light that it will not be likely to disturb the patient as might the use of an open flash light.

A further object is to provide such a device which is convenient to manipulate.

Still another object is to form the device as a casing for the thermometer in which the thermometer may be kept when not in use. By this means the chance of the device not being at hand when wanted is minimized since the casing and the thermometer are normally together.

Still another object as applied to one form of the device is to provide a device which can be used with standard clinical thermometers so that no special thermometer construction is required.

Further objects and advantages will appear from a description of certain embodiments of the invention shown in the accompanying drawings in which

Figure 1 is a plan view of a device embodying the invention and showing the thermometer encased therein.

Figure 2 is a longitudinal sectional view on line 2—2 of Figure 1.

Figure 3 is a view similar to a portion of Figure 2, but showing the thermometer partly removed from the casing.

Figure 4 is an exploded perspective view of the thermometer, a holder therefor, and a light-transmitting element.

Figures 5 and 6 are cross sectional views on lines 5—5 and 6—6, respectively, of Figure 2.

Figure 7 is a right hand end elevation of the device.

Figure 8 is a fragmentary view similar to a portion of Figure 2, but showing a modification.

Figure 9 is a cross sectional view on line 9—9 of Figure 8.

Referring first to the form shown in Figures 1 to 7, there is provided an elongated cylindrical tubular casing 1 having a longitudinal slot 2 for a portion of its length. Within this tubular casing there is housed an element 3, shown detached in Figure 4, this element 3 being provided with a longitudinal groove 4 on one face, terminating near one end with a widened portion 5. This groove 4 provides a seat for a clinical thermometer 6 of standard construction, such thermometers being commonly provided with a widened head portion 7 which may engage with-

2

in the widened portion 5 of the groove 4. Diametrically opposite to the groove 4 is a second groove 10, and in this second groove is positioned a light-transmitting element 11. It has a perpendicular end face 12 against which light may be thrown from a suitable lamp as will later appear. This element is cut off on a diagonal plane to form an inclined face 13, which, when the element is in position in the groove 10, lies against the bottom of this groove.

The intermediate portion of the stock between the grooves 4 and 10 is cut away to form a slot 14 beneath and lengthwise of the thermometer 6 when the thermometer is in position in the groove 4 as shown in Figure 2. The element 3 carrying the light-transmitting element 11 is mounted within the casing 1 and access may be had to the outer end of the slot 4 for removing or replacing the thermometer, past a segmental cover 20 which is hinged to a segmental closure 21 which may be secured to the outer end of the element 3 and bridge over the end of the casing 1. When the thermometer is in position its stem 22 upon which the temperature graduations are marked is positioned beneath the slot 2 of the casing and opposite to the slot 14 in the member 3.

Beyond the inner end of the member 3 the casing 1 may be provided with a transverse partition 25 which contains a socket for the reception of a lamp bulb 26. In order to provide for easy access to this lamp bulb for renewal, or the like, the casing 1 may be formed of two sections having threaded connection with each other at 27 adjacent to the lamp 26.

Back of the partition 25 the casing may house a dry cell battery 28 and a switch element consisting of a button 29 having a shank 30 slideable through the rear end member 31 of the casing which may be employed to control the energization of the lamp 26 from the battery 28. As shown the switch element 29 engages the rear end of the battery 28 which is slidable within the casing 1 and is normally held with its central terminal 32 out of contact with the central terminal 33 of the lamp socket as by means of a coil spring 34. By pressing inwardly on the element 30, the battery may be brought into electrical connection with the socket terminal 33, its outer wall being electrically connected to the opposite terminal as by the spring 34, or the casing 1, or both. The lamp 26 is so positioned that light therefrom impinges against the end 12 of the light conductive element 11 which extends along and adjacent to the thermometer

and is conducted thereby to escape from the face 13, passing through the slot 14 and illuminating the thermometer stem adjacent to the temperature graduations thereof. The casing may be used as a housing for the thermometer when it is not in use so that it is always handy when it is desired to use the thermometer, it being only necessary to open the door 20 to remove the thermometer. After the temperature has been taken it can be returned to the case, and the switch element 30 actuated to illuminate the thermometer so that the temperature reading may be easily ascertained. Since the illumination is directed to the stem of the thermometer and is not allowed to escape in other directions, this may be accomplished without annoyance to the patient, as it produces no bright flash of light which may be visible to him.

In Figures 8 and 9 a modification is shown in which a special thermometer is employed having an inclined longitudinal face 40 back of the graduated face and which may be provided with a reflecting coating of any suitable description which will reflect light received thereagainst which reaches it through a window portion 41 at the inner end of the thermometer adjacent to its bulb. The thermometer is placed in the casing 1a, being housed within an element 3a having a longitudinal slot 4a back of the window portion 2a of the casing. The thermometer is supported with its window portion 41 in position to receive light from the lamp 26a, which may be carried within the casing 1a, in the same manner as the lamp 26 illustrated in Figure 1 and be energized from a battery in the same manner. While as shown in Figure 8, the casing is not provided with a cover to complete the enclosure of the thermometer, of course, if desired, the casing could be extended and a cover provided in the manner shown in Figures 2 and 7.

From the foregoing description of certain embodiments of this invention it should be evident to those skilled in the art that various further changes and modifications might be made without departing from its spirit or scope.

I claim:

1. An elongated casing having a longitudinal socket in which a thermometer may be housed, said socket comprising a longitudinal groove in one face of an element substantially filling one end portion of said casing, said element having another longitudinal groove substantially diametrically opposed to said socket groove, there being a slot in said element between central portions of said grooves, a light-transmitting rod seated in said other groove and having a diagonally cut face positioned opposite to said slot, and a flat end face at the inner end of said element, a lamp carried within said casing in position to direct light against said flat end face to be conducted through said rod and emerge from said diagonally cut face to pass through said slot and illuminate the stem of a thermometer placed

in said socket, and means for energizing said lamp.

2. An elongated casing having a longitudinal socket in which a thermometer may be housed, 5 said socket comprising a longitudinal groove in one face of an element substantially filling one end portion of said casing, said element having another longitudinal groove substantially diametrically opposed to said socket groove, there being a slot in said element between central portions of said grooves, a light-transmitting rod seated in said other groove and having a diagonally cut face positioned opposite to said slot, and a flat end face at the inner end of said element, a lamp carried within said casing in position to direct light against said flat end face to be conducted through said rod and emerge from said diagonally cut face to pass through said slot and illuminate the stem of a thermometer placed in said socket, a battery in said casing, and a switch controlling energy from said battery to said lamp and having an actuating element accessible for actuation externally of said casing.
- 10 25 3. An elongated casing having a longitudinal socket in which a thermometer may be housed, said socket comprising a longitudinal groove in one face of an element substantially filling one end portion of said casing, said element having another longitudinal groove substantially diametrically opposed to said socket groove, there being a slot in said element between central portions of said grooves, a light-transmitting rod seated in said other groove and having a diagonally cut face positioned opposite to said slot and a flat end face at the inner end of said element, a lamp carried within said casing in position to direct light against said flat end face to be conducted through said rod and emerge from said diagonally cut face to pass through said slot and illuminate the stem of a thermometer placed in said socket, said element having a cover for the end of said socket openable to permit the passage of a thermometer into and out of said socket, and means for energizing said lamp.
